UNITED STATES PATENT OFFICE.

TOWNSON HAND, OF ORLANDO, FLORIDA.

WRENCH.

1,163,532.

Specification of Letters Patent.

Patented Dec. 7, 1915.

Application filed May 13, 1915. Serial No. 27,813.

To all whom it may concern:

Be it known that I, TOWNSON HAND, a citizen of the United States, and a resident of Orlando, in the county of Orange and State of Florida, have invented a certain new and useful Improvement in Wrenches, of which the following is a specification.

My present invention relates generally to wrenches and more particularly to a wrench having something of the nature of a combination tool, in that it is particularly adaptable to round surfaces such as pipes and also to polygonal shaped work.

The object of my invention is to provide a wrench which may be instantly adapted to practically any kind of work, which will be extremely simple, speedy in its action, and so arranged that any piece or part may be made or adjusted at any time.

Further objects of my invention will be plainly understood from the following description in which reference is made to the accompanying drawings forming a part of this specification and in which—

Figure 1 is a side elevation illustrating the practical application of my wrench to round work. Fig. 2 is a longitudinal section therethrough in open position, and Fig 3 is an edge view looking toward the left in Fig. 2.

Referring now to these figures, my improved wrench includes a handle A having a series of teeth A' at one end, and projecting at one side, whereby to constitute a rigid jaw A², the handle A having also a slot A³ extending therethrough at the inner end of the rigid head A² formed as described, the inner portion of which head, at the side opposite the teeth A', is provided with a rearwardly presented edge A⁴, thus located at the forward end of the slot A³ for a purpose to be hereinafter described. At an intermediate point, and at the inner end of the slot A³, the handle A is provided with a lateral extension A⁵, having a slot A⁶ therethrough, and having a grooved outer surface as seen at A⁷, the groove forming a seat for one portion of a U-shaped spring B as most plainly seen in Fig. 2.

The movable jaw C which is provided along its inner surface with teeth C' and which is adapted to oppose the rigid jaw A² at the outer end of the handle A, has a laterally extending shank C² at its inner end, which shank extends through the slot A³ of the handle before mentioned, and is pro-

vided along its outer edge with a series of teeth C³, with which the inwardly presented edge A⁴ before mentioned is adapted for engagement in selected adjustment, the shank C² being freely movable through the slot A³ for the purpose of such adjustment, and being normally acted upon by the spring B seated as described, to force the same outwardly against the said inwardly projecting edge A⁴. The free end of the shank C² may have oppositely projecting studs C⁴ to prevent the same from pulling entirely through the slot A³, and thus eliminate danger of its accidental displacement and loss.

The lever D for actuating the movable jaw has a rearwardly extending portion D', forming a handle and extending generally in a direction along the handle A before mentioned, the latter being grooved as indicated at A⁸ to receive the free end of a leaf spring D², the opposite end of which is rigidly connected to the handle D' of the lever. This lever is pivoted, by means of a transverse pivot pin D³, within the slot A⁶ of the lateral extension A⁵ of the handle, and is provided with an angular portion D⁴ projecting through the said slot A⁶ as plainly seen in Fig. 2, said angular portion having at its extremity a forwardly projecting extension D⁵ extending against the inner portion of the movable jaw C and thus offset with respect to the handle D' of the lever D. Thus, with the movable jaw adjusted as shown in Fig. 2, the fulcrum upon which it is movable toward and away from the fixed jaw A², is formed by the inwardly projecting edge A⁴ of the fixed jaw in its engagement with certain of the teeth C³, and pressure is exerted to cause movement of the movable jaw upon its fulcrum so formed, by movement of the handle D' of the lever D toward the handle A as will be seen by a comparison of Figs. 1 and 2.

It is obvious therefore that a wrench so constructed will be simple, cheap and durable, may be instantly applied with equal facility to round and polygonal work, will promote instant release from the object being acted upon by the wrench, upon the release of pressure upon the handle of the lever D, and may be speedily adjusted to vary the particular relative spacing of the movable and fixed jaws.

I claim:—

1. A wrench consisting of a handle having a rigid jaw at one end, and a slot there-

through at the inner end of said jaw, said handle also having an intermediate slotted lateral extension adjacent the inner end of the first mentioned slot, and an inwardly projecting edge at the outer end of the first mentioned slot, a movable jaw having an inner laterally projecting shank extending loosely through the first mentioned slot and provided with a series of teeth along its outer portion for engagement with the said edge at the outer end of the said first mentioned slot to form the fulcrum upon which the movable jaw works, and a lever, the forward portion of which is pivoted within the lateral extension of the handle, and the rear portion of which projects rearwardly along the said handle, the said forward portion of said lever having an offset forwardly projecting extension engaging the movable jaw to rock the same upon its fulcrum.

2. A wrench consisting of a handle having a rigid jaw at one end and an intermediate slot, and provided with an inwardly projecting edge at the outer end of the said slot, a movable jaw opposing the said rigid jaw and having a laterally extending shank projecting through the slot of the handle and provided with a series of teeth for adjustable engagement with the said inwardly projecting edge to form the fulcrum upon which the movable jaw works, and an intermediately pivoted lever carried by the handle, the rear portion of which lever extends rearwardly along the handle, and the forward portion of which extends

laterally through the handle and is provided with a forward rigid extension bearing outwardly against the shank of the movable jaw to rock the same upon its fulcrum.

3. A wrench consisting of a handle having a rigid jaw at one end, and a slot therethrough adjacent the rigid jaw, the movable jaw opposing the rigid jaw and having a shank laterally adjustable through the slot of the handle, relatively engaging means carried by the shank of the movable jaw and a portion of the handle whereby to form an adjustable fulcrum for the movable jaw, and a lever intermediately pivoted to the handle and having a forwardly offset portion bearing against the movable jaw to rock the same upon its fulcrum.

4. A wrench consisting of a handle having a rigid jaw at its outer end, a movable jaw opposing the rigid jaw and having a laterally projecting shank extending through the handle and provided with an adjustable fulcrum, and an intermediately pivoted lever, the rear portion of which extends along the rear portion of the handle, and the forward portion of which extends angularly through the handle and is provided with a forward extension bearing outwardly against the shank of the movable jaw.

TOWNSON HAND.
